UNITED STATES PATENT OFFICE.

JOHN FEA AND WILLIAM H. HOAG, OF AMSTERDAM, NEW YORK.

ARCH-PLATE FOR STEAM-BOILER FURNACES.

SPECIFICATION forming part of Letters Patent No. 448,218, dated March 17, 1891.

Application filed October 29, 1890. Serial No. 369,644. (No model.)

To all whom it may concern:

Be it known that we, JOHN FEA and WILLIAM H. HOAG, citizens of the United States, residing at Amsterdam, in the county of Montgomery and State of New York, have invented certain new and useful Improvements in Arch-Plates for Steam-Boiler Furnaces; and we do hereby declare that the following is a full, clear, and exact description of the invention, which will enable others skilled in the art to which it appertains to make and use the same.

Our invention relates to improvements in the construction of the front and rear arches of steam-boiler furnaces, also roofs of puddling or other furnaces where intense heat is maintained; and it consists in the combination, with the ordinary brick walls of the furnace, of auxiliary or supplementary arches.

It also consists in the special construction of the parts, as will be hereinafter described; and the objects of our improvements are, first, to provide in place of the solid iron arch-plates that are exposed to the direct action of the heat and quickly destroyed a combination-arch, which shall be more durable, and which will protect and sustain the brick-work of the furnace contiguous and adjacent to the arch in a better and more durable manner than any heretofore in use, and, second, to provide for the dispersing of latent heat, so as to reduce expansion and contraction of the parts of which it is composed.

Heretofore in the construction of steam-boiler furnaces iron bars or rails have been used to span the walls of the furnace, transversely, upon which the brick-work has been built. Extreme heat causes the metal of which the rails are composed to expand, warp out of shape, and sag under the weight of the brick, thereby obstructing the passage of heat through the uppermost series of flues of the boiler, and eventually the whole arch collapses. The "throat-plate" or front-door arch of the boiler is also affected in the same manner and frequently melts and collapses.

Referring to the accompanying drawings, Figure 1 is a longitudinal sectional elevation of an ordinary steam-boiler furnace embodying our improvements in relative position with the boiler A and walls B and B'; Fig. 2, a vertical section of a part of our invention

on the line 1 1, Fig. 1, wherein a sectional elevation of the side walls of the furnace is also shown; Fig. 3, an enlarged plan of plates C with portions of the top removed for exposing to view the openings e, leading from the air-chamber E through the bottom of plate C; Fig. 4, a longitudinal section of same on the line 2 2, Fig. 3, wherein is shown the plate C, with the air-chamber E and apertures e leading therefrom, the hollow conoids or brackets d, attached to plate C and spanning openings e, around which a portion of refractory material Q is shown secured to plate C; Fig. 65 5, a sectional transverse view of the hollow plates C C on the line 3 3, Fig. 3, showing the air-chambers E E, also portions or parts of pipe o', carried through the series of brackets or conoids d; and Fig. 6 is a detailed plan of 70 the entire series of openings e in hollow plates C C, with the conoids or brackets d spanning the openings e and a continuous line of pipe o', passing through the brackets d.

Similar letters of reference refer to similar parts throughout the several views.

To carry our invention into effect we construct a metal matrix or hollow form C, of cast or wrought iron, of suitable dimensions to span the walls of the furnace transversely 80 and sufficiently wide to form the arch necessary to be used. In some cases, where a wide arch is required, we prefer to make the chambered form C in two or more sections or parts provided with lugs l l, by which they are held 85 together and secured firmly with bolts. (See Figs. 1, 2, 3, and 5.) The chambered plates or form C have a series of equidistant perforations or apertures e, which communicate with the air-chamber E through one side of the 90 wall of plates C. On the outer or downward side of the plate C the apertures are spanned by an equal number of hollow conoids or brackets d, secured to and formed of the same material as the plates C. The walls of 95 these hollow conoids or brackets d are perforated diametrically, said perforations communicating with the apertures in plate C.

A continuous conduit or line of metal pipe o' is introduced and carried through the apertures in the conoids d, (see Fig. 6,) said pipe being made in sections and joined together with close-fitting elbow-joints, as shown, and is made to connect with the air-chamber E at

- one end of plate C by means of the elbow e^2 . The pipe o' is somewhat smaller in diameter than the apertures in conoids or brackets d , so as to allow fire-clay or other refractory material Q in a plastic state to be packed between the pipe o' and walls of the conoids or brackets d and into all the cavities or apertures in the brackets d , and said refractory material Q is also applied to the surface of the plate around and over the conoids d and pipe o' , so as to cover all portions of said conoids and pipe and inclose the same, so that they will be substantially wholly embedded with in the body of the plastic refractory material Q. The plastic material Q is made of fire-clay or ground fire-brick, or a mixture of both, or other refractory material or ingredients—as for instance, the compound described in Letters Patent No. 248,651.
- 20 In the operation of applying the plastic material over the surfaces to be protected the said material is to be worked over and about the conoids or brackets d , so as to clinch and hold with the perforated walls of same and 25 be securely held and retained in place against the plate C wholly and substantially by means of the perforated conoids or brackets d . (See Figs. 1, 2, and 4.)
- The refractory material Q may be applied 30 before or after the plates C are placed in the walls of the furnace; but we prefer to pursue the latter course, as the plates can be more easily handled and more perfect jointing effected with the walls. (See Figs. 1 and 2.)
- 35 The terminal end of pipe o' serves as a supply-pipe to lead cold air from a convenient source to the conduit-pipe o' , through which it rushes by its own pressure by way of the elbow e^2 into chamber E, wherein the air, 40 rarefied by the furnace heat, has produced a partial vacuum and passed through connecting-pipe N into the second chamber E, the rarefied air in which having passed from same by natural draft through the outlet-pipe P, 45 which is constructed (but not shown in drawings) to have access to the atmosphere outside the boiler-house. The apertures e , spanned by the perforated brackets d , allow the moisture in refractory compound while in a plastic 50 state, especially that portion contiguous to metal plates C and brackets d , to evaporate and escape into the air-chamber E; allow su-

perfluous heat communicated to the compound or material Q, while the furnace is being operated, to enter chamber E and escape through the vent or pipe P. The perforations e also tend to prevent expansion of the plates C by making them non-conducting, and it is evident that a circulation of air through the chamber E will dispel the moisture that arises and afterward disperse the latent heat as rapidly as it is generated. 55

It will of course be understood that the front and rear arches, as shown in Fig. 1, are similar in the main points of construction, 60 having slight minor differences in their conformation to correspond with the configuration of the furnace parts to be protected.

The chambered plates C and their component parts may be made either straight, 70 curved, or arched to suit the purpose without changing the nature of our invention.

Having fully described our invention, what we claim jointly, and desire to secure by Letters Patent, is—

1. The combination, with the front and rear walls in a steam-boiler furnace, of hollow chambered perforated plates provided with hollow metallic conoids or brackets secured to the plates and spanning the perforations 80 in the plates, said hollow conoids or brackets having parts or portions of their walls perforated or removed, whereby a refractory compound or material can be held and secured to the plates, all substantially as specified. 85

2. The combination of the hollow chambered metal plates perforated and spanned by hollow perforated conoids or brackets d , the conduit-pipe o' , passing through the perforations in the brackets d and held in place by the 90 refractory material, the elbow e^2 , the connecting pipe N, the outlet-pipe P, and the refractory compound or material Q, secured to the plates C by means of the perforated conoids or brackets d , as described, all adapted to be 95 used, substantially as and for the purpose specified and set forth.

In testimony of which we have signed our names in the presence of two witnesses.

JOHN FEA.

WILLIAM H. HOAG.
